No. 880,066.

PATENTED FEB. 25, 1908.

C. DEEG.

CONCRETE SIDEWALK BLOCK.

APPLICATION FILED AUG. 1, 1907.

UNITED STATES PATENT OFFICE.

CHARLES DEEG, OF MADISON, WISCONSIN, ASSIGNOR OF ONE-THIRD TO PETER WEILER
AND ONE-THIRD TO CHARLES H. FIX, OF MADISON, WISCONSIN.

CONCRETE SIDEWALK-BLOCK.

No. 880,066.

Specification of Letters Patent.

Patented Feb. 25, 1908.

Application filed August 1, 1907. Serial No. 880,632.

To all whom it may concern:

Be it known that I, CHARLES DEEG, a citizen of the United States, and resident of Madison, in the county of Dane and State of Wisconsin, have invented certain new and useful Improvements in Concrete Sidewalk-Blocks; and I do hereby declare that the following is a full, clear, and exact description thereof.

10 The object of my invention is to provide a simple, durable and economical portable sidewalk block, the said block being designed with a view to molding and curing the same under cover at convenient localities for distribution to be thereafter laid as the demand requires.

15 The construction and arrangement of the blocks is such that in laying they interlock each other, requiring no specially prepared bed and in consequence can be quickly assembled into a sidewalk by unskilled labor.

20 The invention therefore consists in various novel structural features and combination of parts as hereinafter fully set forth with reference to the accompanying drawings and subsequently claimed.

25 In the drawings: Figure 1 represents a plan view of a portion of a sidewalk composed of assembled concrete blocks made in accordance with my invention; Fig. 2, a sectional elevation of the same, as indicated by line 2—2 of Fig. 1; Fig. 3, an end elevation of the sidewalk partly in section, as indicated by line 3—3 of Fig. 1; Fig. 4, a side elevation 30 partly broken away and in section to better illustrate the details, and Fig. 5, an inverted plan view of a portion of one of the blocks.

35 Referring by numerals to the drawings, 1 indicates the body-portion of the cement 40 blocks, the cross-wise edges of which are provided with parallel oblique faces 2, 3, the oblique face 2 being matched and arranged to be overlapped by the overhanging oblique face 3 of the next block, in order that a flush 45 supporting-joint between the same is had. The face 3 of each block is also slightly beveled at its edge adjacent the upper surface of the block, said bevel forming together with the opposite bevel face 2 of the next block, a 50 V-shaped groove crosswise of the side-wall. The oblique faces 2, 3, are formed with rectangular grooves 4, which grooves are matched with those of the grooves of the other blocks to constitute squared apertures 55 for the reception of similarly shaped pins 5

that are fitted therein and serve as means for interlocking the blocks, the pins being preferably provided with heads whereby they may be withdrawn in case it is desired to remove a block. It is obvious however that in place of forming the grooves as described, they may be semicircular in shape, in which case round interlocking pins would be used in place of short pins, in either case, rods extending across the entire width of the block 60 could be utilized.

The blocks have integral side-stringers 6 projecting from their under surfaces, end-extensions 7 of which stringers extend beyond the body of the blocks adjacent to the 70 oblique faces 3 thereof. Said end-extensions 7 terminate with oblique faces 8 corresponding to said oblique faces 3 as shown, and the upper surfaces of these end-extensions are also slightly convexed to form rests 75 for the opposite ends 9 of stringers 6 of the next block which are supported thereon. The opposite ends 9 of the stringers terminate flush with the adjacent oblique faces 2 of the blocks, and these ends are cut-away for 80 a portion of their depth, the length of which cut is equal to the length of their opposite extending ends 7, the faces of the cut-away-portions being concaved and terminating in oblique end-faces 10, the inclines of which 85 face correspond to those of the oblique edge faces 2 of the blocks.

From the foregoing description it will be seen that when the blocks are laid, their respective stringer-ends, in connection with 90 the oblique edge faces of said blocks form interlocking matched joints, which joints are secured by the pins to hold the blocks against longitudinal play, while the said interlocking joints preserve perfect longitudinal alignment and support. As shown, the bodies of the blocks are preferably provided with anchor-rods or tubes 11 molded therein to add stiffness and strength to the material, the stringers being similarly provided with 95 rods or tubes 12.

While I have shown the rods or tubes as running in both directions in the body of the cement-blocks, in some instances the longitudinal rods may be dispensed with, 105 wherein the blocks are placed over metal girders of cellars or excavations which extend under a sidewalk.

As shown in Fig. 3 of the drawings, under 110

ordinary conditions the blocks are laid directly upon the ground which is excavated to form a seat for the stringers, there being an air-space between the ground and body of the blocks as shown. By this arrangement any frost which might accumulate would be free to rise out at either edge of the stringers, the resistance offered thereby being so slight as not to cause displacement or serious damage.

I claim:

1. A cement sidewalk block comprising a flat body-portion having parallel lateral oblique-faced ends, matched grooves in the oblique faced ends, the grooves being adapted to receive locking-pins, longitudinal stringers depending from the body-portion of the block at right-angles to said oblique-faced ends, and stringer end-extensions projecting beyond said body-portion, the opposite ends of the stringers being cut away for a distance equal to the length of the end-extensions aforesaid.

2. A cement sidewalk block comprising a flat body-portion having parallel lateral oblique-faced ends, matched grooves in the oblique-faced ends, the grooves being adapted to receive locking-pins, longitudinal stringers depending from the body-portion of the blocks at right-angles to said oblique-faced ends, end-extensions of the stringers projecting beyond said body-portion, oblique inclined faces at the ends of the extensions and parallel with the adjacent oblique end-faces of the block, cutaway-portions at the opposite ends of the stringers, the cutaway portions conforming in shape to the reverse contour of end-extensions aforesaid, whereby matched-joint connection is had between stringers of an adjacent block.

3. A cement sidewalk block comprising a flat body-portion having parallel lateral oblique-faced ends, matched grooves in the oblique-faced ends, the grooves being adapted to receive locking-pins, longitudinal stringers depending from the body-portion of the block at right-angles to said oblique-faced ends, end-extensions of the stringers projecting beyond said body-portion, the end-extensions terminating in oblique faces and having convexed upper surfaces, and cutaway-portions at the opposite ends of said stringers, the cutaway portions conforming in shape to the reverse contour of the end-extensions aforesaid, whereby matched-joint connection is had between stringers of an adjacent block.

4. A cement sidewalk block comprising a flat body-portion having anchor-rods embedded therein and parallel lateral oblique-faced ends, rectangular matched grooves in the oblique-faced ends, the grooves being adapted to receive squared locking-pins, longitudinal stringers depending from the body-portion of the block at right-angles to said oblique-faced ends, anchor-rods embedded in the stringers, and stringer end-extensions projecting beyond said body-portion, the opposite ends of the stringers being cut away for a distance equal to the length of the end-extensions aforesaid.

In testimony that I claim the foregoing I have hereunto set my hand at Madison in the county of Dane and State of Wisconsin in the presence of two witnesses.

CHAS. DEEG.
